UNITED STATES PATENT OFFICE.

ALAN R. FERGUSSON, OF BUFFALO, NEW YORK.

TOY SIGNAL TOWER.

Application filed January 26, 1923. Serial No. 614,967.

To all whom it may concern:

Be it known that I, ALAN R. FERGUSSON, a citizen of the United States, residing at Buffalo, in the county of Erie and State 5 of New York, have invented certain new and useful Improvements in Toy Signal Towers, of which the following is a specification.

This invention relates to toy devices such 10 as toy semaphore signal towers, and particularly to a toy or miniature stand or upright support upon which may be mounted supporting arms for suitable signal means or the like, an object of the invention being 15 to provide an improved device of this general class which will be cheap in construction, easy to manufacture, strong and durable in use.

Other objects of this invention will appear 20 in the following description thereof, reference being had to the accompanying drawings forming a part of this specification, wherein like reference characters indicate corresponding parts in the several views 25 and wherein Fig. 1 is a front side elevation illustrating a semaphore tower; Fig. 2 is a rear elevation thereof; Fig. 3 is a sectional plan view taken on line 3—3 of Fig. 1; Fig. 4 is an enlarged fragmentary view partly 30 in section illustrating the manner in which a semaphore arm may be connected to the upright; Fig. 5 is a cross section taken on line 5—5 of Fig. 4; Fig. 6 is a rear elevation illustrating a toy telegraph pole embodying 35 certain features of my invention and Fig. 7 is a cross section on line 7—7 of Fig. 6.

Before explaining in detail the present improvement and mode of operation thereof, I desire to have it understood that the invention 40 is not limited to the details of construction and arrangement of parts which are illustrated in the accompanying drawings, since the invention is capable of other embodiments, and that the phraseology 45 which I employ is for the purpose of description and not of limitation.

Heretofore, in toy devices such as semaphore signal towers or the like, the manufacture thereof has been such, due to the 50 character and cost of material used, the character of construction and the large number of steps necessary in order to complete the making of the devices, as to render the devices relatively expensive so that it has 55 been impossible to sell the same cheaply in

five and ten cent stores. Furthermore, where devices of this class heretofore made were constructed with a sheet metal base and an upright formed of sheet metal tubing, a relatively flimsy and weak structure resulted 60 and hence such devices did not have the durability which is desirable in the case of toy devices which receive hard usage. By virtue of the present invention however, applicant has constructed a toy signal device 65 which is not only considerably cheaper than any heretofore made but a great deal stronger and more durable in use. The supporting stand in general is preferably formed from a single length of wire bent to form a coiled 70 base and a supporting upright. This stand can be made in a single operation and due to the cheapness of material and labor necessary for making this stand it can be produced cheaply enough for sale in the five and 75 ten cent stores. And in addition the stand is practically indestructible.

Referring to the drawings it will be seen that the toy semaphore signal tower preferably comprises a stand which is formed by 80 bending up a single length of wire of suitable size and length, the stand thus comprising a coiled base 9 in which the wire is bent inwardly at 10 in the plane of the base and bent upwardly from the center of the coil 85 to form an upright supporting member 11. The upright 11 is provided with imitation steps for the imaginary purpose of climbing the tower, these steps comprising elongated lugs or projections 12 squeezed or forced out 90 of the metal of the wire upright. In the present instance the imitation steps are arranged alternately at opposite sides of the upright member 11.

In the present instance the supporting 95 stand is provided with a pair of swinging semaphore arms 14 which are directly pivoted or connected to the wire upright or post 11. The latter is pressed or flattened out at 13 to form flat portions to which the flat 100 sides of the arm 14 may be readily attached as by means of rivets 15. By virtue of this construction wire of relatively small diameter may be utilized, yet the semaphore arm may nevertheless be pivoted by means of 105 rivets or other suitable means directly to the wire post, so that by increasing the size or width of the post at such places I thus provide enough surface for the rivet or other attaching device to pass through the wire. 110

This construction considerably cheapens the manufacture of the device since it eliminates the necessity of using a supplementary clamp for attaching the semaphore arm to the wire post.

Each semaphore arm 14 is preferably stamped out of sheet metal and at its inner end beneath the pivot 15 is provided with an elbow or offset portion 16. This elbow or offset end may be provided with suitable self-locking means for automatically locking the arm in various adjusted positions. In the present instance the self-locking means also forms means adapted to serve the purpose of imitation signal lights. This self-locking means comprises a pair of spaced circular depressions or indentations 17, which on the front side of the signal tower as shown in Fig. 1, may be lithographed in different colors to imitate signal lights, or instead of painting or lithographing the colored lights, colored paper disks 19 may be pasted in the circular depressions. At the rear side of the signal tower these depressions 17, as shown in Figs. 2 and 4, form bulges or projections 18 forming a groove therebetween for receiving the wire post 11.

When the semaphore arm is swung on its pivot 15 from its lowered position, one of the projections 17 will frictionally engage the wire post 11, and the resiliency of the arm will permit the projection 17 to pass over the post and permit the latter to become lodged or gripped in the groove between the bulges 18. The semaphore arm may be maintained in various angular positions due to the fact that either locking projection 18 will grip the wire post 11 at various points on its surface and hold the arm in such adjusted position. In the construction illustrated in Figs. 6 and 7 certain features of the invention are shown as adapted to a toy or miniature telegraph pole. In this instance the supporting stand also preferably comprises a single length of wire bent to form a coiled base 20 and an upright supporting post 21. The wire post is also provided with integral elongated projections 22 pinched or forced out from the metal of the wire so as to form imitation ladder steps. The cross arms 23 of the telegraph pole may be stamped out of a single piece of sheet metal so as to form therebetween metal connecting portions 24 which may be bent or clamped around the wire post 21 thereby securing the cross arms 23 in position.

It is to be understood that by describing in detail herein any particular form, structure or arrangement, it is not intended to limit the invention beyond the terms of the several claims or the requirements of the prior art.

Having thus explained the nature of my said invention and described a way of con-

structing and using the same, although without attempting to set forth all of the forms in which it may be made, or all of the modes of its use, I claim:

1. In a toy railway accessory the combination of supporting means including an upright member and a swinging signal or semaphore member directly pivoted to said upright member, one of said members having an integral projection forced therefrom to engage the other member for maintaining the signal member in various positions. 70

2. In a toy railway accessory, the combination of supporting means including an upright member, and a swinging signal or semaphore arm directly pivoted to said member and having a pair of parallel projecting portions at its rear cooperating with the upright member for maintaining the arm in various positions. 75

3. In a toy railway accessory, the combination of supporting means including an upright member, and a swinging signal or semaphore arm directly pivoted to said member and having a depression adapted to form locking means at one side for maintaining the arm in various adjusted positions and signal means at the opposite side. 85

4. In a toy railway accessory the combination of supporting means including an upright wire member compressed to form a flattened portion and a swinging or semaphore arm member pivoted directly to said flattened portion, one of said members having an integral projection forced therefrom in position to engage the other member for maintaining the arm member in various positions. 95

5. In a toy railway accessory, the combination of supporting means including an upright wire compressed to form a flattened portion, and a signal or semaphore arm pivoted directly to said flattened portion and having a depression adapted to form signal means at one side and wire engaging means 105 at the other to maintain said arm in any of its adjusted positions. 110

6. In a toy railway accessory, the combination of a wire formed base having an upright wire provided with a flattened portion, and a signal or semaphore arm directly pivoted to said flattened portion and having an angularly located portion provided with a pair of parallel depressions adapted to frictionally engage the wire to maintain the arm 115 in any of its adjusted positions, the opposite sides of said depressions forming imitation signal lights. 120

7. In a toy railway accessory, the combination of supporting means including an upright wire, said wire having at opposite sides thereof ladder forming projections, pressed therefrom. 125

8. In a toy railway accessory, the combination of supporting means comprising a 130

wire base and an upright wire, said wire having at opposite sides thereof ladder-forming projections pressed therefrom.

9. In a toy railway accessory, the combination of supporting means including an upright wire having ladder-forming projections pressed from said wire and also having a flattened portion, and a signal or semaphore arm directly pivoted to said flattened portion.

5 10. In a toy railway accessory, the combination of supporting means including an upright wire having ladder-forming projections pressed from said wire and also having a flattened portion, and a signal or semaphore arm directly pivoted to said flattened portion.

15 10. In a toy railway accessory, the combination of supporting means including an upright wire having ladder-forming projections pressed from said wire and also having a flattened portion, and a signal or semaphore arm directly pivoted to said flattened portion and provided with a depression effective to frictionally engage the upright wire and maintain the arm in any of 20 its adjusted positions.

25 11. In a toy railway accessory, the combination of supporting means including an upright wire having ladder-forming projections pressed from said wire and also having a flattened portion, and a signal or semaphore arm directly pivoted to said flattened portion and provided with a depression effective to frictionally engage the upright wire and maintain the arm in any of 30 its adjusted positions, the opposite side of said depressed portion forming an imitation signal light.

35 12. In a toy railway accessory, the combination of supporting means including an upright member, and a swinging signal or semaphore arm directly pivoted to said member and having a projecting portion at its rear cooperating with the upright member for maintaining the arm in various 40 positions, said upright member having ladder-forming projections pressed therefrom.

45 13. In a device of the class described, a support comprising a base and a wire upright post, said post having a widened portion, and a signal arm pivoted to said portion, said arm having depressions adapted to form locking means at one side and signal means at the opposite side.

50 14. In a device of the class described, a support comprising a single length of wire bent to form a coiled base and an upright post, said post having an integral flattened portion, and an arm connected to said portion, said arm having depressions adapted

55 to form locking means at one side and signal means at the opposite side, said upright wire post having pressed-out portions forming imitation ladder steps.

15 15. In a device of the class described, a support comprising a single length of wire 60 bent to form a coiled base and an upright post, said post having an integral pressed portion, and an arm connected to said portion, said arm having imitation signal lights at one side and self-locking means at the opposite side and adapted to engage said wire post for locking the arm in predetermined position.

16 16. A toy railway accessory comprising a wire formed supporting base having an 70 integral vertical wire member provided with a flattened portion, and a swinging signal or semaphore arm directly pivoted to said flattened portion.

75 17. In a toy railway accessory, the combination of a wire-formed base having one end extended to form a radially disposed portion terminating in a single upright wire post having a flattened portion, and a swinging signal or semaphore arm pivoted 80 directly to said flattened portion and carrying a projection at one side for frictionally engaging the upright wire to maintain the arm in any of its adjusted positions.

85 18. In a toy railway accessory, the combination of supporting means including an upright member having a flattened portion, and a stamped-out sheet metal signal or semaphore arm directly pivoted to said flattened portion for swinging movement, said 90 arm having a depressed portion in position to frictionally engage the upright member to maintain the arm in any of its adjusted positions.

95 19. In a toy railway accessory, the combination of supporting means including an upright member having a flattened portion, and a stamped-out sheet metal signal or semaphore arm directly pivoted to said flattened portion for swinging movement, said 100 arm having a depressed portion in position to frictionally engage the upright member to maintain the arm in any of its adjusted positions, said depressed portion forming an imitation signal light at the opposite side. 105

Signed at Buffalo, N. Y., this 24th day of January, 1923.

ALAN R. FERGUSSON.
